US00D914833S

(12) **United States Design Patent** (10) **Patent No.:** **US D914,833 S**
(45) **Date of Patent:** **** Mar. 30, 2021**

(54) **CRYOGENIC CONTAINER INSERT**

(71) Applicant: **Packaging Technology Group, Inc.**,
Fall River, MA (US)

(72) Inventor: **William C. Blezard**, Mattapoisett, MA
(US)

(73) Assignee: **Packaging Technology Group, Inc.**,
Fall River, MA (US)

(**) Term: **15 Years**

(21) Appl. No.: **29/692,879**

(22) Filed: **May 29, 2019**

(51) LOC (13) Cl. **23-01**

(52) U.S. Cl.

USPC **D23/202**

(58) **Field of Classification Search**

USPC D23/200-205

CPC F17C 13/08; A61M 29/00

See application file for complete search history.
